(57) **CLAIM**

The ornamental design for the gun slide grip, as shown and described.

DESCRIPTION

FIG. 1 is a front view of the gun slide grip.

FIG. 2 is a rear view of the gun slide grip.

FIG. 3 is a left side view of the gun slide grip.

FIG. 4 is a right side view of the gun slide grip.

FIG. 5 is a top view of the gun slide grip.

FIG. 6 is a side perspective view of the gun slide grip disposed on a gun slide.

FIG. 7 is a top view of the gun slide grip disposed on a gun slide; and,

FIG. 8 is a side view of the gun slide grip disposed on a gun slide.

The broken lines depict environmental and non-claimed subject matter and form no part of the claimed design.

The bottom view of the gun slide grip is omitted as being merely duplicative of the provided Figures.

1 Claim, 3 Drawing Sheets
